UNITED STATES PATENT OFFICE.

ROBERT L. McMURRAN, OF PORTSMOUTH, VIRGINIA.

DAUBER.

No. 912,719.

Specification of Letters Patent.

Patented Feb. 16, 1909.

Application filed July 22, 1908. Serial No. 444,770.

To all whom it may concern:

Be it known that I, ROBERT L. McMURRAN, a citizen of the United States, residing at Portsmouth, in the county of Norfolk 5 and State of Virginia, have invented new and useful Improvements in Daubers, of which the following is a specification.

This invention relates to a dauber for applying liquids or watery solutions such 10 as are generally used for polishing shoes, stoves and furniture or for other purposes to which it may be applicable.

The primary object of the invention is to provide a dauber of simple construction and 15 operation for effectively applying polishing liquids or other solutions without soiling the hands and having an organization of elements that may be readily associated and cheaply manufactured.

20 The invention consists in the construction and arrangement of the several parts which will be more fully hereinafter specified.

In the drawing: Figure 1 is a perspective view of a dauber embodying the features of 25 the invention and showing a part thereof separated or detached. Fig. 2 is a section taken longitudinally through the dauber with all the parts in associated relation.

Similar characters of reference are employed to indicate corresponding parts in 30 the views.

The numeral 1 designates an elongated tubular body which may be constructed of any suitable material, either metal, 5 pressed paper, fiber or a suitable composition, but whatever material is used it is proposed to reduce the cost of manufacture to a minimum so that the dauber complete may be commercially introduced and sold at 40 small cost. The upper part of the body 1 is formed as a supply reservoir 2 which extends from about mid-way of the body fully to one extremity of the latter and is closed by a removable cap 3 provided with a yielding diaphragm 4 for effectively forcing the 45 contents of the reservoir 2 downwardly towards the feeding end of the dauber by pressing on the said diaphragm. The outlet extremity 5 of the reservoir 2 is reduced and 50 communicates with a rotatable or plug valve 6 extending transversely through the body 1 and exteriorly operative by means of a key 7, the valve 6 being provided with a suitably shaped opening 8. Beyond the location of 55 the valve 6 the body is continued to form an extension 9 having an exteriorly screw-

threaded terminal to removably receive a closing cap 10. The extension 9 has a feeding nozzle 11 concentrically arranged therein and terminating at a distance inwardly from 60 the free end of the extension 9. The bore 12 of the nozzle 11 is in direct alinement with the reduced outlet 5 of the reservoir 2 and communication between the said outlet and bore of the nozzle is controlled by the valve 65 6. It will be seen that the valve 6 prevents the contents of the reservoir 2 from passing downwardly or into the feed nozzle 11 when the valve is closed as shown by Fig. 2, and by this means flooding of the extension of 70 the dauber with the contents of the reservoir is prevented when the dauber is not in use and leakage and waste is thus avoided.

The liquid passing through the feed nozzle 11 is delivered to an absorbent wad, 75 sponge, or other analogous material 13 constituting a swab and held in place in the free end of the extension 9 of the body by friction instituted through the medium of a resilient holder or clip 14 of substantially 80 U-shaped form and which is embedded in the swab as shown by Fig. 2. This simple means of holding the swab 13 within the extension 9 of the body 1 provides for a ready replacement of one swab that may have become worn by another of a similar absorbent characteristic and also insures a retention of the swab in place in the extension 9. As shown, the swab 13 is projected outwardly 85 beyond the free end of the extension 9 so as 90 to render it serviceable as a medium for applying the contents of the reservoir 2. When the dauber is not in use the cap 10 is applied to the extension 9 and covers the projected portion of the swab 13. 95

The reservoir 2 is filled by removing the pressure cap 3 and subsequent to the filling operation this cap is reapplied. When it is desired to use the dauber the cap 10 is detached and the valve 6 opened or turned so 100 that the opening 8 therein will coincide with the outlet extremity 5 of the reservoir and the bore 12 of the feed nozzle 11 and thereby permit the contents of the reservoir to pass into and through the nozzle to the swab 13. 105 When the dauber is not in use the valve 6 is closed, as shown by Fig. 2, for reasons hereinbefore explained.

The arrangement of the nozzle 11 within the extension 9 as specified is advantageous 110 in that an economical feed of the contents of the reservoir 2 in central relation to the

swab 13 will ensue without unnecessarily flooding and clogging the interior of the extension with quick drying liquid. It will be understood that the feed of the contents 5 of the reservoir downwardly into or through the nozzle 11 will be facilitated by exerting a pressure on the diaphragm 4 in the event that the passage of the contents of the reservoir through the valve and into the nozzle 10 becomes sluggish.

The dauber will be found exceptionally useful for the purpose for which it has been devised and it is particularly cleanly in its operation, and the feed of the contents there- 15 of to the swab 13 may be economically pursued with advantage in avoiding the application of the liquid contents of the dauber too rapidly or in quantities greater than desired.

20 One of the main advantages of the foregoing organization is the arrangement of the swab 13 and its retention in the end of the extension 9 so that its support will be independent of the nozzle 11 and also where- 25 by it may be adjusted towards and from the extension of the nozzle to insure a practical absorption as well as flow of the liquid contents of the dauber and to regulate the distance of the swab with relation to the 30 outlet end of the nozzle to compensate for liquids having varying consistency and differ- 35 ing as to their readiness to be taken up by the material of which the swab is composed. The swab may also be readily re- 40 moved from the extension 9 to facilitate cleaning the said extremity and the nozzle 11, and by employing the resilient holder 14, which may be cheaply made, as a means for retaining the swab in place, considerable 45 economy results in the cost of manufacture of the dauber as it is unnecessary to provide any other interior means for holding the swab in place.

Having thus described the invention, what 45 is claimed as new, is:

1. A dauber comprising a body having a reservoir, an extension and an outlet nozzle inclosed within the extension, a feed controlling valve between the reservoir and nozzle, and an absorbent swab held in the extension of the body independently of the nozzle and adjustable with relation to the latter.

2. A dauber comprising a body having a reservoir in one portion thereof and an extension with an inclosed nozzle, a feed controlling valve interposed between the reservoir and nozzle, an absorbent swab held in the extension of the body independently of the nozzle, a removable cap applied to the extension of the body over the swab, and a pressure cap removably applied over the reservoir end of the body. 60

3. A dauber comprising a body having a reservoir in one portion thereof and an extension with a nozzle inclosed therein, and an absorbent swab adjustably mounted in the extension and supported independently of the nozzle, the inner portion of the swab being normally spaced from the outlet end 70 of the nozzle.

4. A dauber comprising a body having a reservoir in one portion thereof and an extension with a feed nozzle inclosed therein, and an absorbent swab removably and adjustably mounted in the extension and hav- 75 ing a resilient holder to exert a pressure be- 80 tween the same and the wall of the extension.

5. A dauber comprising a body having a reservoir in one portion thereof and an extension with a feed nozzle inclosed therein, and an absorbent swab adjustably and removably mounted in the extension and pro- 85 vided with a U-shaped resilient holder par- 90 tially embedded therein and serving to retain the swab in the extension.

6. A dauber comprising a body having a reservoir extending longitudinally through a portion thereof, a pressure cap removably applied to the inlet end of the reservoir, the body having an extension continuous with the reservoir portion thereof and provided with an inclosed nozzle, a feed controlling valve interposed between the reservoir and nozzle, and an absorbent swab supported in the free end of the extension independently 95 of the nozzle.

In testimony whereof I have hereunto set my hand in presence of two subscribing witnesses.

ROBERT L. McMURRAN.
